MACHINES FOR PACKING TEXTILES
Conrad Arbter, Saal (Saale), Lower Franconia, Germany
Filed Mar. 13, 1959, Ser. No. 799,252
3 Claims. (Cl. 53—180)

The present invention relates to a machine for packing textiles in a synthetic foil wrapping closed on all sides. By "synthetic foil wrapping" is meant in connection with the present invention a wrapping which contains the goods in an envelope which is closed on all sides. A wrapping closed on all sides has been obtained for textile goods, in other words soft goods by placing the goods in a bag open at one end and then tightly sealing the said open end. Such procedure, however, always requires the inconvenience of introducing the textiles, for instance laundry articles, into the bag.

There are also known machines for packing articles in a synthetic foil wrapper closed on all sides. Such machines are equipped with a device for stepwise feeding two sheets or foils which at least at the end of their feeding path have their edges moved closely above each other and parallel to each other and which receive the goods therebetween. Such machines are furthermore equipped with a device for fusing the foils or sheets around the goods and for cutting off the fused foil portions. The device for feeding the foils or sheets is, within the range of the edges of said foils and parallel thereto, equipped with endless belts which, by means of the belt sections facing each other, clamp the foil edges therebetween. Such machines, however, are not suitable for packing soft goods into a very soft wrapping material.

It is, therefore, an object of the present invention so to improve heretofore known packing machines that the above mentioned drawbacks will be overcome.

It is another object of this invention so to improve the above mentioned heretofore known wrapping machines that they will also be able to wrap soft goods in synthetic foil wrappers closed on all sides.

These and other objects and advantages of the invention will appear more clearly from the following specification in connection with the accompanying drawings, in which:

FIG. 1 is a side view partly in section of an improved wrapping machine according to the present invention.

FIG. 2 is a top view of FIG. 1 with the foils shown therein omitted.

The machine according to the present invention is characterized primarily in that steel conveyor belts or conveyor belts of similar stiff material for instance hard synthetic material are employed and at the side of the foils are provided with depressions or perforations.

Referring now to the drawings in detail, the machine shown therein comprises a machine frame 11 having journalled thereon in bearings (not shown) shafts 35 and 37 which have keyed thereto pulleys 36 and a drum 38 for a pair of endless steel conveyor belts 39. Pulleys 30 and 31 respectively mounted on shafts 33 and 78 support an upper pair 32 of conveyor belts. A stationary auxiliary frame 24 has journalled thereon shafts 49 and 51 with pulleys 50 and 52 respectively for a pair of steel belts 53. A fourth pair of steel belts 48 is movable over rollers and drums 41, 43, 45, and 47 the shafts of which are designated with the reference numerals 40, 42, 44 and 46 respectively. The lower part of frame 11 carries a pair of bearing supports 27 for a drum 28 carrying a spool with a wound-up foil strip 29. This foil strip is adapted to move between the pairs of steel belts 39 on one hand and the steel belts 32 and 48 on the other hand to a pair of end rollers 55, 77 respectively mounted on shafts 54 and 56 at the right-hand end of the machine with re-

2

gard to FIG. 1. The auxiliary frame 24 furthermore carries a drum 25 for another spool of wound-up foil strip 26 which passes between the pairs of conveyor belts 53, 48 and 39 and 48 to the said pair of end rollers 55.

- 5 Within the range between the pulleys 43 and the drums 38, 45 there are thus located the two foil strips 26 and 29 as upper and lower foil strips arranged adjacent each other at least at the edges thereof. These conveyor belts are designed as steel belts and are at the sides of the foils
- 10 provided with depressions or perforations such as the perforations 32a for cooperation with the foils. These foils slightly penetrate into the depressions or perforations thereby assuring a positive clamping and movement of the foils. The perforations may also cooperate with
- 15 sprocket wheels (not shown in the drawing). The belts may be driven by an electric motor 12 mounted on the lower portion of machine frame 11. In order to avoid an unnecessary clogging up of the drawing, the means for conveying the torque to the individual conveyor belts
- 20 have been omitted. Motor 12 is designed for stepwise drive or for stepwise drive with a single revolution clutch or the like. In addition to the above mentioned equipment for stepwise feeding the two foil strips, the machine is furthermore equipped with a device for stepwise
- 25 depositing the goods 63 shown by way of example as a shirt upon the lower foil strip section 29. To this end, a slide or carriage 58 with a plate 58a is mounted on a bracket 57 arranged at the left-hand end (with regard to FIG. 1) of the machine. The goods 63 are placed
- 30 upon the said plate 58a by an operator and aligned by engaging an abutment 62. Slide 58 is provided with skids 61 movable on a pair of rails 60 and on a roller 64 journalled on a shaft 69. The said plate 58a can be moved from the position shown in the drawing toward the
- 35 right until the skids 61 engage the roller 64. In this last mentioned end position, the goods 63 will be above the lower foil strip section 29 and below a holding plate 67. Holding plate 67 is by means of guiding bushings 68a movable upwardly and downwardly on a pair of columns
- 40 68. The movement of said holding plate 67 is effected by means of a magnet 72 and a pull rod 70. A return spring 71 surrounding the pull rod 70 is adapted, when the magnet is deenergized, to return the holding plate 67 to the position shown in FIG. 1.
- 45 The device for fusing together the foil strips 26 and 29 around the goods and for cutting off the fused foil sections, is arranged at the right-hand side of the machine with regard to FIG. 1. For this purpose, the shaft of drive motor 12 has mounted thereon a sprocket wheel 13
- 50 which, through the intervention of a sprocket chain 14, drives a sprocket wheel 79 mounted on an eccentric shaft 16. The said eccentric shaft 16 also has mounted thereon a pair of lower sprocket wheels 20 by means of which an upper pair of sprocket wheels 21 is driven through the
- 55 intervention of a pair of sprocket chains 15. The said pair of sprocket wheels 21 is mounted on an upper eccentric shaft 18. Each of the two eccentric shafts 16 and 18 is journalled in frame 11 in any convenient manner and is provided with a lower and upper eccentric 17 and
- 60 19 respectively. These eccentrics are adapted by means of pressure members 23 to act upon upwardly and downwardly movable welding plates 22 equipped with welding rails 80. The shaft of motor 12 has connected thereto a crank disc 81 with a connecting rod 75 adapted to move
- 65 a welding and cutting device 76 upwardly and downwardly in guiding means 73.

The described machine operates in the following manner. It may be assumed that the machine has been in operation for some time and that the upper foil strip 26 as well as the lower foil strip 29 have been inserted between the conveyor belts and extend up to the pairs of end rollers 55, 77. At certain intervals corresponding

to the respective operating rhythm, a piece of goods will be located on the lower foil strip. The goods of the last half of the feeding path are simultaneously covered by the upper foil strip 26. One of the pieces of goods will also be located between the welding plates 22 which at the start of the work are spaced from each other. However, no piece of goods will at this time be below the holding plate 67.

If now a new piece of goods 63 is placed upon plate 58a and the latter is moved from its left end position shown in FIG. 1 into its right-hand end position, the newly deposited piece of goods will be located below the holding plate 67. At the same time, however, also plate 58 reaches the limit switch 66 so that the latter is actuated and closes the energizing circuit for magnet 72 which thereupon performs a single working stroke. As a result of the energization of magnet 72, pull rod 70 pulls holding plate 67 downwardly so that the latter engages the piece of goods. When now plate 58a is moved back to its starting position by spring 71, the piece of goods 63 is held in its position below the holding plate 67, in particular also due to the downwardly bent left-hand edge of plate 67, and the piece of goods 63 rests upon the foil section 29. When the slide plate 58 returns to its left-hand position, one of the skids 61 actuates a limit switch 65. This in turn brings about deenergization of magnet 72 so that spring 71 can return holding plate 67 to its starting position. Drive motor 12 performs a single revolution. This brings about an advance of the various conveyor belts by one step and thereby causes the belts to move the foil strips 26 and 29 and the workpiece 63 located thereon and therebetween by one feeding step. The welding or fusing device will with a corresponding time delay, due to the drive by means of the eccentrics 17, 19 bring about a movement of the welding plates 22 toward each other and thereby a welding of the foil strips along three sides of the piece of goods. The left transverse side will for the time being remain open, i.e. not yet welded or fused. In the same cycle the welding plates 22 move away from each other. During the same working cycle, the welding and cutting device 76 will, by means of the crank drive 81, 75, two feeding steps fur-

ther, produce the fourth welding seam and the separating cut adjacent said last mentioned welding seam. The pair of end rollers 55, 77 will then at the end of each feeding step over a slide 82 discharge a piece of goods enclosed in a foil wrapper fused on all four sides.

It is, of course, to be understood that the present invention is, by no means, limited to the particular construction shown in the drawings but also comprises any modifications within the scope of the appended claims.

10 As a hard synthetic material for the conveyor belts 32 etc. may be selected polyvinyl chloride.

What I claim is:

1. In a machine for packing articles in a synthetic foil envelope closed on all sides: a plurality of pairs of endless steel conveyor belts with depressions therein, the belts of each of said pairs of belts being laterally spaced from and substantially parallel to each other for respectively receiving and supporting and conveying foil strips therebetween along a certain feeding path, driving means drivingly connected to said conveyor belts and operable to advance the same by steps, said pairs of conveyor belts including at least near the end portion of said path superimposed portions of at least two of said pairs of said belts, parallel to and closely arranged relative to each other so as tightly to clamp therebetween marginal portions of the respective adjacent foil portions with the article to be packed therebetween, and fusing and cutting means arranged near said end portion of said path for fusing said foils around said article and cutting the fused portions of said foils off from the remainder of said foils.
2. A machine according to claim 1, in which said endless conveyor belts are of sheet metal steel.
3. A machine according to claim 1, in which the depressions are in the form of perforations.
